(57) **CLAIM**

The ornamental design for a tyre, as shown and described.

DESCRIPTION

FIG. 1 is a perspective view of a tyre in accordance with our new design;

FIG. 2 is a right side view thereof;

FIG. 3 is a left side view thereof; and,

FIG. 4 is a front elevation view thereof.

The part of the drawings shown with a reduced tonal value, along with the broken-line perimeter, illustrates a portion the tyre that forms no part of the claimed design.
